UNITED STATES PATENT OFFICE.

FRANK COATES, OF CLEADON, AND JAMES MIRREY, OF EAST BOLDON, ENGLAND, AS
SIGNORS TO A REYROLLE & COMPANY, LIMITED, OF HEBBURN-ON-TYNE, ENGLAND, A COMPANY OF GREAT BRITAIN.

OIL-IMMERSED ELECTRIC SWITCH.

Application filed June 27, 1925, Serial No. 40,915, and in Great Britain August 30, 1924.

This invention relates to oil-immersed electric switches and more particularly to what are usually termed switch fuses, i. e. devices in which the lid of a metal box carries on its under surface insulating supports for a removable fuse which, when the lid is closed, completes a circuit between two fixed conductors mounted within the box and immersed in oil.

According to the present invention instead of the outer lid or cover carrying the fuse or switch member, an inner lid or frame is provided for that purpose and is adapted to be moved in relation to an outer lid or cover so that the contacts may be opened or closed whilst the cover remains closed.

The inner lid is preferably so disposed in relation to the outer lid or cover that it must be raised to open the circuit before the cover can be opened or closed. In other words, if the cover is closed the movable contacts, i. e. those supported on the inner lid or frame, must be separated from the fixed contacts before the cover can be opened, or if the cover is open it cannot be closed unless the inner lid is in such a position that the contacts will remain separated until after the cover has been closed. Thus the circuit making and breaking operations always take place whilst the outer cover is closed.

Conveniently between the cover and the inner lid, mechanism is provided which is operated by the movement of a catch or fastening device for the cover. This catch may be so arranged that when the cover is closed and the catch engaged with a lug on the box or tank, the act of disengaging the catch first raises the inner lid and then allows the cover to be opened. Conversely unless the inner lid remains in its new position relatively to the cover the catch will foul the lug so that the cover cannot be closed.

When the inner lid has been raised to separate the movable and fixed contacts, the two lids preferably move together and swing right back so that access to the fuse on the underside of the inner lid may be easily and safely obtained.

In a preferred construction according to this invention the movement of a catch to release the outer cover rotates, by means of a toothed quadrant and pinion, a spindle carried on the underside of the cover. This spindle carries at each of its ends a lever connected by a link to the inner lid so that

on rotating the spindle by means of the catch the inner lid is raised and the contacts separated before the release of the outer cover. Should the lids move relatively to one another while the outer cover is open, then the catch will foul the lug with which it engages when the box is closed, thereby preventing accidental closure of the box with the contacts in the "on" position. The inner lid is provided with a spring or springs in order to effect a quick opening or closure of the contacts when the spindle has been turned beyond a certain position.

The invention may be carried out in various ways, but one construction is illustrated by way of example in the accompanying drawings in which:—

Figure 1 shows an end view of the apparatus with part of the casing removed and the contacts in the closed position.

Figure 2 is a partial section on the line 2—2 of Figure 1.

Figure 3 is an outside elevation showing the catch mechanism, and

Figure 4 is a view similar to Figure 1, but showing the contacts in the open position and the outer cover closed.

In the drawings the box A, which is adapted to contain oil, is provided with an outer cover A¹ supported on hinges A², and having hinged to it at B¹ an inner lid B, on the underside of which are mounted the insulated supports C which carry the contacts D and fuse E. Mounted in bearings F on the underside of the outer cover A¹ is a short spindle G which projects through the cover and carries rigidly secured to its outer end a catch H and operating lever J. Inside the cover, on the spindle G is mounted a toothed quadrant K engaging a pinion L secured to a spindle M. This spindle runs the length of the box and is supported in bearings N on the underside of the outer cover. At each end of the spindle M is a lever O connected by a link P to the inner lid B and a spring P¹ is provided between the link P and the outer cover A¹ to ensure a rapid opening or closure of the inner lid B and its contacts D.

The catch H cooperates with a lug A⁴ on the side of the box A, and lugs H¹ and A⁵ (Figure 3) are provided on the catch and the side of the box respectively through which a padlock H² may be inserted to lock the inner lid in the closed position. Simi-

larly other lugs A⁶ and H³ are provided to lock the inner lid in the open position if desired. The mechanism is so arranged that in order to raise the outer cover A¹ the catch H must first be disengaged from the lug A⁴ and in so doing the spindle G is partially rotated, this motion being transmitted by means of the toothed quadrant K and pinion L to the spindle M. The levers O rotate with the spindle M and commence to lift the inner lid B by means of the links P and after the levers O have reached their dead-center position the springs P¹ effect a rapid further opening of the lid and consequent separation of the contacts D and R. Other springs B² are provided between the inner lid and outer cover, which normally tend to open the inner lid. These also contribute to the quick movement of the contacts when opening.

On the complete disengagement of the catch H the outer cover A¹ is immediately opened say by means of overbalance weights which are not shown in the drawings but may be mounted on arms, parts of which are shown at S, or the cover may be opened by hand, in which case counter-balance weights may be provided. The outer cover on opening carries with it the inner lid and fuse, which may then be easily and safely inspected or replaced.

To close the box again the outer cover A¹ is first shut down and the inner lid is afterwards closed by the replacement of the catch H fastening down the cover A¹. Should the catch have been rotated accidentally while the box is open, it will foul the lug A⁴ if any attempt is made to close the outer cover with the inner lid in a position in which the contacts would be liable to close before the outer cover were properly fastened down.

Preferably some other means of securing the outer cover A¹ in addition to the catch H are provided such as swing bolts A⁷ or other usual fastening or clamping devices, and the cover may be furnished with a padlock A⁸ for locking it in the closed position.

The fixed and movable contacts within the box may be of any suitable construction, and the fuse may be supported in blocks attached to the insulating supports on the inner lid in any convenient way but preferably so that the fuse can be readily removed and replaced.

Preferably, however, as in the construction illustrated, butt-on contacts are employed, in which case the removable fuse E is provided at each end with a clamping member E¹ connected by a tension spring E² to a spring-sided block E³ which can be pushed into position in a holder C¹ adapted to receive it and mounted on the insulated support C. The holder is hollow and contains a sliding stem terminating in the contact button D which, when the contacts are closed, is

pressed firmly against the fixed contact R by means of the spring D¹.

The electrical connection between the contact button D and the block E³ is preferably made by means of a flexible connection D². The clamping member E¹ of the fuse is electrically connected to the block E³ by flexible connectors E⁴ so that the springs E² are not relied upon for current-carrying purposes, but serve to hold the fuse in tension and to separate the two parts thereof when it is blown.

It will be appreciated that in a switch fuse box constructed according to this invention the contacts can never be closed while the box is open nor can they be opened from the closed position except whilst the outer cover is closed.

What we claim as our invention and desire to secure by Letters Patent is:—

1. In an electric switch, in combination, an oil box having fixed contacts therein, a lid hinged to said box, an inner contact carrying frame hinged to said lid within said box, a spindle passing through one wall of the lid and carrying outside the lid a catch engaging with a fixed part of the box to secure the lid in closed position, a toothed gear inside the lid operatively connecting the spindle with the inner frame so that partial rotation of the spindle to release the catch causes an upward swing of the inner frame toward the lid, said catch being so disposed as to prevent opening or closing of the lid except when the frame is raised toward the lid.

2. In an electric switch, in combination, an oil box having fixed contacts therein, a lid hinged to said box, an inner contact carrying frame hinged to said lid within said box, a spindle passing through one wall of the lid and carrying outside the lid a catch engaging with a fixed part of the box when the spindle is rotated, a toothed gear on the spindle inside the lid, a second spindle mounted on the lid, a gear wheel carried by the second spindle and meshing with the gear on the first spindle, a crank on the second spindle and a link connecting the crank member with the hinged inner frame so that movement of the fastening device to release or fasten the lid raises or lowers the inner frame.

3. A device as claimed in claim 2 which further includes in combination a spring attached to said crank and said lid in such a manner as to assist the rapid raising and lowering of said frame.

4. A device as claimed in claim 2 which further includes in combination, a plurality of elongated insulators depending from the inner frame, spring pressed butt-on contacts carried at the lower ends of said insulators and fuses connected between each pair of contacts by flexible conductors.

5. In an electric switch box having an inner and an outer lid the combination with a fuse member carried by the inner lid of fixed contacts within the box with which the 5 fuse member makes connection when the inner lid is closed, a rotatable spindle mounted on the outer lid, a fastening device for the outer lid carried on said rotatable spindle, a toothed quadrant also carried on the rotatable spindle, a second spindle mounted on the outer lid, a gear wheel carried by this second spindle and engaging the toothed quadrant, a crank member mounted on the same spindle as the gear wheel and a link 10 connecting the crank member with the inner lid so that the movement of the fastening device to release or to fasten the outer lid raises or lowers the inner lid.

6. In an electric switch box having an inner and an outer lid the combination with a fuse member carried by the inner lid, of fixed contacts within the box with which the fuse member makes connection when the inner lid is closed, a fastening device for the outer lid, operative connections between said fastening device and the inner lid such that the movement of the fastening device to release or to fasten the outer lid raises or lowers the inner lid and a lug on the box with which the fastening device engages when the outer lid is closed such lug being so positioned that it will foul the fastening device if an attempt be made to close the outer lid unless the inner lid is in the raised position and the circuit consequently open.

7. In an electric switch box having an inner and an outer lid the combination with a fuse member carried by the inner lid of fixed contacts within the box with which the fuse member makes connection when the inner lid is closed, a rotatable spindle mounted on the outer lid, a fastening device for the outer lid carried on said rotatable spindle, a toothed quadrant also carried on this spindle, a second rotatable spindle mounted on the outer lid, a gear wheel mounted on this spindle and engaging the toothed quadrant, a crank member mounted on the same spindle as the gear wheel, a link connecting the crank member and the inner lid so that the movement of the fastening device to release or to fasten the outer lid raises or lowers the

inner lid and a lug mounted on the box with which the fastening device engages when the outer lid is closed such lug being so positioned that it will foul the fastening device if an attempt be made to close the outer lid unless the inner lid is in the raised position and the circuit consequently open.

8. In an electric switch box having an inner and an outer lid the combination with a fuse member carried by the inner lid of spring pressed butt-on contacts, fixed contacts within the box with which the butt-on contacts make connection when the inner lid is closed, a fastening device for the outer lid, operative connections between said fastening device and the inner lid such that the movement of the fastening device to release or to fasten the outer lid raises or lowers the inner lid and means for preventing the outer lid from being closed unless the inner lid is in the raised position and the circuit consequently open.

9. In an electric switch box having an inner and an outer lid the combination with a fuse member carried by the inner lid of spring pressed butt-on contacts, fixed contacts within the box with which the butt-on contacts make connection when the inner lid is closed, a rotatable spindle mounted on the outer lid, a fastening device carried by said spindle, a toothed quadrant also carried by this spindle, a second rotatable spindle mounted on the outer lid, a gear wheel mounted on the second spindle and adapted to engage the toothed quadrant, a crank member carried by the same spindle as the gear wheel, a link connecting the crank member and the inner lid so that the movement of the fastening device to release or to fasten the outer lid raises or lowers the inner lid and a lug mounted on the box with which the fastening device engages when the outer lid is closed, such lug being so positioned that it will foul the fastening device if an attempt be made to close the outer lid unless the inner lid is in the raised position and the circuit consequently open.

In testimony whereof we have signed our names to this specification.

FRANK COATES.
